ELECTROMAGNETIC REGULATOR

Friedrich Menzel, Stuttgart, Germany, assignor to
 Robert Bosch Gesellschaft mit beschränkter
 Haftung, Stuttgart, Germany

Application April 15, 1939, Serial No. 268,115
 In Germany April 22, 1938

3 Claims. (Cl. 171—229)

The present invention relates to an electromagnetic regulator for dynamo-electric machines of electric installations including those suitable for use on vehicles, and having a resistance 5 which may periodically be switched in series with the exciting winding of the dynamo.

In the known regulator constructions of installations of this type the resistance to be switched in before the exciting winding is formed mostly as a 10 special or separate part of the apparatus, and is of suitable material which for example is fitted in the base of the regulator.

It is also known, in regulators having only one regulator contact, which effects the periodic 15 switching in of the resistance before the exciting winding, to apply this resistance in the form of a demagnetising winding, or so called bucking coil, beside the voltage coil on the electromagnet of the regulator.

According to the present invention a component part of the voltage coil of the regulator 20 acting wholly in the same direction serves as the resistance to be switched in before the exciting winding of the dynamo.

For this purpose the voltage coil of the regulator is tapped at such a place, that at the instant of regulation the same ampere windings are effective at all positions of the regulator contact.

The arrangement according to the present invention has the advantages over the known construction with a resistance in the form of a trembler coil that firstly the resistance need not be wound as a special or separate coil, but can 35 be wound as a unit with the voltage coil of which it forms a part and secondly the construction is suitable for regulators with several regulator contacts whilst the known regulators can only be constructed with one regulator contact.

The invention is more particularly described with reference to the accompanying drawing which shows schematically by way of example, one form of construction voltage regulator for 45 dynamos suitable for use on automobiles or other vehicles.

In the drawing the armature 1 and an exciting winding 2 form the dynamo. A voltage coil 4 wound about a magnet core 3 of the voltage 50 regulator is divided at the place of division 5 into parts 41, 42 in such a manner that the part 41 can serve as a switched in resistance for the exciting winding 2.

An armature 6 carries regulator contacts 7, 8 55 respectively adapted for make and break with

opposed fixed contacts 9 and 10. A spring 11 operates to draw the armature 6 into that position of rest in which the contacts 7 and 9 are closed. For the sake of completeness an automatic charging switch 12 and a battery 13 are diagrammatically shown in the drawing.

The number of windings of the parts 41 and 42 of the voltage coil together with their resistance values are so chosen that in each of the subsequently described regulation positions of 10 the contacts 7, 8, 9, 10 the same number of ampere turns are active. The voltage coil 4 can thereby consist of parts composed of the same or different material. The voltage is regulated in a manner known in bucking regulators. 15

On the putting into operation of the dynamo the part 41 of the voltage coil serving as a switched in resistance is short circuited by the closed contacts 7, 9. The voltage evolved by the dynamo assumes the value commensurate with 20 the resistance of the exciting winding 2. Thus only the part 42 of the voltage coil 4 lies at the voltage evolved by the dynamo under these conditions.

If on account of increasing speed of the dynamo 25 the voltage and therewith the current flowing through the part 42 has attained a predetermined value, then this current together with the windings of the part 42 requires a definite number of ampere turns at which the voltage regulator attracts its armature 6 against the pull of the spring 11, and thereby separates the contacts 7 and 9, so that all the regulator contacts are open. At this moment when the part 41 is switched in before and in series with the exciting winding 2, to which the part 42 lies parallel, the same ampere turns are active as in the foregoing regulation position with closed contacts 7 and 9, by reason of the corresponding choice of the resistance and number of windings of the 30 parts 41 and 42 as a result of the partial current flowing through the part 42, and of the total current flowing through the part 41.

At higher speeds of rotation the armature 6 closes the contacts 8, 10, whereby the exciting 45 winding 2 and simultaneously the part 42 of the voltage coil 4 are short circuited. In the current circuit there lies now only the part 41, which commensurate with its number of turns and its resistance value, together with the current flowing 50 through it at this instant, has again in this contact position, the same number of ampere turns as was attained in the foregoing regulation positions.

By the invention is thus obtained a regulator, 55

in which, while avoiding a special or separate switched in resistance for the exciting winding, a part of the voltage bobbin serves as a switched in resistance and which, in spite of this, has the same electromagnetic force in each regulating contact position.

I declare that what I claim is:

- 5 1. The combination, with a dynamo-electric machine, having an exciting winding, for electric installations on vehicles, of an electromagnetic regulator comprising a magnet core, a voltage coil wound about said magnet core and acting wholly in the same direction of magnetization, an armature, a contact operated by 10 said armature, a fixed contact in the electric circuit of said machine for engagement with the contact operated by said armature, and a conductor lead extending from said exciting winding and the contact operated by said armature 15 to a point of said voltage coil intermediate the ends thereof to divide said coil into two component parts, one of which component parts operates as a resistance switchable periodically in series with said exciting winding by said contacts.
- 20 2. A regulating system for dynamo-electric

machines such as for lighting and charging installations on vehicles comprising, in combination, a dynamo-electric machine having an exciting winding, a circuit including said winding, and an electromagnetic regulator in said circuit 5 and comprising only one voltage coil having a component part adapted to act as a resistance and wholly in the same direction magnetically as said voltage coil, said regulator also including an armature and contacts controlled thereby for 10 periodically connecting said resistance in series with said exciting winding.

3. In a regulating system for dynamo-electric machines such as for lighting and charging installations on vehicles, the combination comprising 15 a dynamo-electric machine having a field circuit, a resistance for said field circuit, and an electromagnetic regulator in said field circuit for periodically switching said resistance in said field circuit, said regulator including only one 20 voltage coil having a component part adapted to act as said resistance and wholly in the same direction magnetically as said voltage coil.
